Patented Oct. 18, 1966

206,023

SERVICE INDICATING AND CHARTING BOARD

Louis E. Reghitto, Walnut Creek, Calif.
(1113 10th St., Antioch, Calif.)

Filed Mar. 17, 1965, Ser. No. 84,323

Term of patent 14 years

(Cl. D52—6)

Fig. 1

Fig. 2

FIGURE 1 is a front isometric view of a service indicating and charting board showing my new design.

FIGURE 2 is a bottom view of the board.

The rear of the service indicating and charting board is plain in appearance. The dominant features of the design are shown in full lines.

I claim:

The ornamental design for a service indicating and charting board, substantially as shown and described.
